ATTACHMENT FOR LADDERS

Fred D. Randall, Dayton, Ohio

Application October 9, 1941, Serial No. 414,372

14 Claims. (Cl. 228—60)

This invention relates to an attachment for ladders which may be readily attached to and detached from different sizes of ladders such as those used for painting buildings and the like, said attachment being provided with adjustable means serving primarily two purposes namely, first, to brace or stabilize the ladder when the same is leaning against the building or the like, and second, to enable the ladder to be positioned in a vertical position when the ladder is standing on an inclined, irregular or uneven surface.

In the use of ladders for the painting of buildings, washing windows and the like it is sometimes difficult to stand the ladder in a position convenient for the purposes of the person working thereon. This is true particularly when the part of the building against which the ladder is to be leaned comprises a curved surface or a cornice, or when it is desired to position the top of the ladder directly in front of a window. The device of the present invention comprises a ladder attachment provided with arms which are adjustably extensible laterally so as to bridge a window, cornice or the like to provide a bearing for the ladder against the side of the building and yet hold away from the part to be worked on. The device of the present invention furthermore provides a means for giving lateral support for the ladder when it is leaned against either a flat or a curved surface so as to stabilize the ladder when so positioned as well as to brace the ladder to prevent tipping thereof which might otherwise result from the overbalancing effect produced when the workman leans or reaches to one side.

The device of the invention is so constructed that the adjustable arms may be adjusted so as to provide a level footing for the ladder to position the same vertically when the ladder is standing on inclined or uneven ground.

The device of the invention is so constructed as to enable the same to be readily attached to and detached from various sizes of ladders commonly used without mutilating or requiring any constructional change to be made in such ladders.

Other objects, advantages and features of novelty will appear more fully as the description of the invention progresses in conjunction with the accompanying drawings in which:

Figure 1 is a top plan view of a ladder attachment embodying my invention and showing the same attached to a ladder.

Figure 2 is a front view.

Figure 3 is a sectional view taken on the line 3—3 of Figure 1.

Figure 4 is a detailed view of a modification of part of the device shown in Figure 1.

Figure 5 is a sectional view of the outer end of one of the arms of the device showing a pointed surface engaging foot attached thereto.

Figure 6 is a detailed view of the outer end of one of the arms showing a different form of a surface engaging foot attached thereto.

Figure 7 is a side view of a modified form of the attachment of my invention showing same attached to a ladder in a manner to support the ladder in vertical position when supported on an inclined ground surface.

Figure 8 is a top plan view of the modified form of the ladder attachment shown in Figure 7, Figure 8 showing the attachment used to support the ladder relative to a vertical surface against which the ladder is to be leaned.

Figures 9 and 10 are detail views of one of the laterally adjustable arms of the modified form of device of Figures 7 and 8, showing the means for adjustably securing the auxiliary arm thereto.

Now describing the invention in detail, the numeral 1 indicates the stiles or side pieces, and the numeral 2 the rungs of a ladder to which the attachment device of the invention may be attached. The attachment device itself comprises a frame which embraces the ladder consisting of a frame member 3 which preferably is formed of square tubing, brackets 4 and 5 secured in any desired manner to the frame member 3 and engaging the outer sides of the ladder stiles 1; and an adjustable clamping frame member 6 adjustably secured to the brackets 4 and 5 as by means of bolts 7 adapted to extend through suitable apertures in the clamping frame member 6. The bolts 7 may be secured to the brackets 4 and 5 in any suitable manner as by means of welding, or, as shown by bracket 4' in Figure 4, the brackets 4 and 5 may be formed with an angled piece such as 4'a provided with an aperture for receiving the bolt 7'. The frame member 6 may be secured on the bolts 7 or 7' by means of suitable wing nuts 8 as shown.

One or both of the brackets 4 and 5 may be of a U form such as the bracket 5 as shown in Figure 1, and the side 5a of said bracket may engage one of the rungs 2 from above the same to position the attachment vertically relative to the ladder. The sides of bracket 5, or either of the brackets 4 and 5 if U shaped brackets are used in both instances, will be spaced far enough

apart so as to accommodate ladder stiles of various thicknesses. The brackets 4 and 5 will be spaced far enough apart to accommodate ladders of various widths.

The clamping frame member 6 is provided with a laterally adjusting clamping bracket 9. For this purpose the clamping frame member 6 is formed with an elongated slot 10 which receives the bolt or stud 11 of the bracket 9 which may be secured in adjusted position relative to the frame member 6 by means of a wing nut 12. The clamping bracket 9 is provided with a lug 13 which also engages in the slot 10 for properly positioning the bracket 9. The angled portion 9a of the bracket 9 is clampingly engageable with the inner side of one of the ladder stiles 1.

Arms 14 and 15 are adjustably associated with the frame member 3 and said arms are provided with angled portions 14a and 15a which are preferably angled outwardly as seen best in Figure 1 and are preferably angled slightly upwardly as seen best in reference to Figure 2. The upward angling of the outer ends 14a and 15a of the arms is to enable said portions of said arms to be positioned more nearly horizontally when the same engage the building against which the ladder is to be positioned in view of the fact that the ladder will be somewhat inclined from vertical when so positioned. The arms 14 and 15 are preferably formed of U channel members or of square tubing as seen best in Figure 3 so that the arms 14 and 15 will not rotate relative to the frame member 3 when inserted therein and clamped thereto by means of the clamping screws 16 and 17 which latter are suitably threaded through the frame member 3 so that the inner ends of said screws may engage the arms 14 and 15.

In attaching the device of the invention to a ladder, the nuts 8 may be removed from the bolts 7 to permit removal of clamping frame member 6 therefrom, whereupon the device is positioned so that the brackets 4 and 5 engage the outer sides of the stiles 1 and the inner side 5a of the bracket 5 may engage one of the rungs 2 above the same to vertically position the attachment relative to the ladder. The clamping frame member 6 may then be assembled on the bolts 7 and clamped up tightly against the ladder stiles 1 and the clamping bracket 9 suitably adjusted into clamping engagement with the inner side of one of the ladder stiles 1. The arms 14 may then be laterally adjusted relative to the frame member 3 and clamped in the desired position by means of the thumb screws 16 and 17.

If the surface against which the ladder is to be leaned includes a protruding curved surface such as indicated by the dotted line 18 in Figure 1 the arms 14 may be laterally adjusted so as to bridge this curved surface and engage with the straight wall indicated by the line 19 in Figure 1. It will be apparent also that the arms 14 and 15 may be adjusted suitably so that they will engage the curved surface and yet provide adequate lateral support for the ladder.

As shown by Figure 5 the ends 14a and 15a of the arms 14 and 15 may have inserted in their hollow outer ends foot members such as 20 comprising a shank 21 suitably received in the hollow outer ends of said arms and provided with a point 21a for digging into the surface against which the arms are engaged to assist in preventing lateral movement of the ladder. Alternatively the outer ends 14a and 15a of the arms 14 and 15 may be provided with rubber feet such 75

as indicated at 22 in Figure 6 which fit over the ends of said arms.

A modification in reference to the adjustable arms 14 is shown by Figures 7, 8, 9, 10 construction. In this modification the arms 14' and 15' are likewise formed either square or of U channel shape similar to the arms 14 and 15 previously described, and the arms 14' and 15' are likewise receivable within the hollow, square tube frame member 3 to be clamped at various positions of adjustment relative thereto by means of the set screws 16 and 17 as described in reference to the arms 14 and 15. However, instead of having the angled portions 14a and 15a of the arms 14 and 15, the arms 14' and 15' are provided at their ends with the adjustable arms 23 and 24.

The arms 14' and 15' are formed at their ends with sleeve portions 25 and 26 which receive respectively the arms 23 and 24. The sleeve portions 25 and 26 are provided with set screws 27 and 28 respectively which engage in holes 23a and 24a provided at intervals throughout the length of the arms 23 and 24. The arms 23 and 24 may be provided with foot members 29 and 30 respectively which preferably may be flat on the bottom so as to provide adequate support when said foot members are resting upon the ground to position the ladder in vertical position or when said foot members are resting against a vertical surface against which the ladder may be leaned. The members 29 and 30 are universally connected to their respective arms as by means of the ball and socket connection shown.

In the use of the attachment device shown in the modification in Figures 7, 8, 9, 10, the same may be attached to a ladder in the same way as described in reference to the construction of Figures 1 to 4. When it is desired to lean the ladder against a wall which is irregular such as that indicated by the dotted line 31 in Figure 8, the arm 23 will be adjusted relative to the arm 14' so as to engage one portion of the wall 31, and the arm 24 will be differently adjusted relative to the arm 15' to engage the protruding portion of the wall 31 whereby the width of the ladder will be positioned parallel to the building when leaned against the wall 31.

Figure 8 also shows how the device may be adjusted to position the ladder relative to a vertical wall 31a when the surface upon which the ladder is standing, such as a sidewalk or the like, runs at an angle or in a direction not parallel to the wall 31a against which the ladder is to be leaned.

While Fig. 8 shows the feet 29 and 30 parallel to the line 31a, it will be understood that said feet are shiftable, due to their universal connection, into parallel relation to the particular surface, such as 31 or 31a, against which the ladder may be supported.

When the device of the modification is desired to be used to support the ladder in vertical position on an inclined ground surface such as indicated at 32 in Figure 7, all that is necessary to do is to remove the arms 14' and 15' from the frame member 3 after unloosening the thumb screws 16 and 17 and then to reinsert the arms 14' and 15' in the frame member 3 so that the arms 23 and 24 will be in vertical position relative to the ladder instead of in horizontal position relative to the ladder as they were in Figure 8. Now the arms 23 and 24 may be adjusted relative to the arms 14' and 15' so as to compensate for the difference in level of ground at the points of engagement of the foot members 29

and 30 whereby the ladder may be positioned in vertical position while supported on the inclined ground surface 32.

Thus it will be apparent that the ladder attachment device of the modification of Figures 7 to 10 is useful for two purposes namely, to support the ladder against the side of a vertical wall such as the side of a building or to support the ladder in vertical position when standing on inclined or irregular ground and to accommodate the device for the performance of either of these objects all that is necessary is to change the positioning of the arms 14 and 15 relative to the square tubing frame member 3 so that the arms 23 and 24 will either be in a vertical position relative to the ladder or in a horizontal position relative to the ladder.

Except for the differences referred to, the modified construction of Figures 7 to 10 is otherwise similar to the construction of Figures 1-6, and the parts correspondingly designated in the several figures are the same. It will be understood that the tubular frame member 3 may be round rather than square as shown, but I prefer to make it with an internal angular configuration and to have the arms 14 and 15 (as well as arms 14' and 15') of a fitting correspondingly angled configuration so as to insure against rotation of said arms relative to the frame member 3 when said arms are clamped in the desired adjusted position.

Having thus described my invention, and what I claim as new and desire to secure by Letters Patent of the United States is:

1. In a supporting attachment for ladders, in combination, a frame detachably securable to a ladder and comprising opposing frame members adapted to extend transversely across the ladder, means for clampingly engaging said members with the ladder from opposite directions, means on said members for engaging opposite sides of the ladder, and a clamping member adjustably associated with one of said frame members for clampingly engaging one of the ladder stiles in a direction opposed to the direction of engagement of said second means, and a pair of arms adjustable relative to said frame laterally of said ladder for supporting the ladder relative to a surface against which said arms are engaged.

2. A supporting attachment for ladders as claimed in claim 1 wherein the second means includes a member engageable with a rung of the ladder.

3. A supporting attachment for ladders as claimed in claim 1, wherein the second means comprises a pair of spaced bracket members secured to one of said frame members and the first means comprises a clamping bolt on each of the bracket members, said bolts extending through the other of said frame members.

4. A supporting attachment for ladders as claimed in claim 1, wherein one of said frame members is provided with a longitudinal slot, and said clamping member comprises an angle bracket, a clamping bolt thereon extending through said slot, and a lug on said bracket engaging in said slot.

5. A supporting attachment for ladders as claimed in claim 1, wherein the second means comprises a pair of spaced bracket members secured to one of the frame members, one of said bracket members having a portion engageable with a rung of the ladder.

6. A supporting attachment for ladders as

claimed in claim 1, wherein the second means includes a pair of spaced bracket members secured to one of said frame members, and the first means comprises a clamping bolt on each of the bracket members, said bolts extending through the other of said frame members, and wherein one of said frame members is provided with a longitudinal slot and said clamping member comprises an angle bracket, a clamping bolt thereon extending through said slot, and a lug on said bracket engaging in said slot.

7. In a supporting attachment for ladders, in combination, a frame detachably securable to a ladder and comprising a sleeve adapted to extend transversely of the ladder, a pair of arms telescopically receivable in opposite ends of said sleeve with the ends of said arms extending therefrom, means for adjusting the arms laterally of the ladder to different fixed positions relative to said sleeve, an auxiliary arm associated with each of said first arms for movement in a direction substantially transverse to the direction of adjusting movement of the first arms, and means for adjusting the auxiliary arms to different fixed positions transversely of the first arms, said first arms being adjustable relative to the sleeve to position the auxiliary arms in either a substantially vertical or a substantially horizontal position relative to the ladder.

8. In a supporting attachment for ladders, in combination, frame means detachably securable to a ladder and comprising opposing frame members adapted to extend transversely across the ladder, means for clampingly engaging said members with the ladder from opposite directions, and means associated with said frame means for clampingly engaging one of the ladder styles in a direction transverse to the direction of clamping engagement of said members, and a pair of arms adjustable relative to said frame means laterally of said ladder for supporting the ladder relative to a surface against which said arms are engaged.

9. In a supporting attachment for ladders, in combination, frame means detachably securable to a ladder and comprising opposing frame members adapted to extend transversely across the ladder, means for clampingly engaging said members with the ladder from opposite directions, and means associated with said frame means for clampingly engaging one of the ladder styles in a direction transverse to the direction of clamping engagement of said members, said last means comprising a clamping member adjustably associated with one of said frame members, and a pair of arms adjustable relative to said frame means laterally of said ladder for supporting the ladder relative to a surface against which said arms are engaged.

10. A supporting attachment for ladders as claimed in claim 8 wherein one of said means includes a member engageable with a rung of the ladder for vertically positioning the frame relative to the ladder.

11. In a supporting attachment for ladders, in combination, frame means detachably securable to a ladder, a pair of arms associated with said means and laterally adjustable relative to a ladder, said arms having portions extending from the same in a direction transverse to the direction of lateral adjusting movement, and said arms being adjustable to position said portions in either a substantially vertical or a substantially horizontal position relative to the ladder, whereby said arms may support the ladder rela-

tive to either a ground surface or a substantially vertical surface.

12. In a supporting attachment for ladders, in combination, frame means detachably securable to a ladder, a pair of arms laterally adjustable relative to said frame means, and an auxiliary arm associated with each of said first arms and adjustable in a direction transverse to the direction of adjusting movement of the first arms, said first arms being adjustable relative to said frame means to position the auxiliary arms in either a substantially vertical or a substantially horizontal position relative to the ladder.

13. In a supporting attachment for ladders, in combination, frame means detachably securable to a ladder and comprising opposing frame members adapted to extend transversely across the ladder and clampingly engageable with the ladder from opposite directions, means associated with said frame means for clampingly engaging one

of the ladder styles in a direction transverse to the direction of clamping engagement of said members, a pair of arms laterally adjustable relative to said frame means and an auxiliary arm associated with each of said first arms and adjustable in a direction transverse to the direction of adjusting movement of the first arms, said first arms being adjustable relative to said frame means to position the auxiliary arms in either a substantially vertical or a substantially horizontal position relative to the ladder.

14. A supporting attachment for ladders as claimed in claim 8, and members universally connected to the outer ends of said arms and having surface engaging portions, whereby said last members will adapt themselves to differently inclined surfaces against which the same are engaged.

FRED D. RANDALL.
